UNITED STATES PATENT OFFICE.

EBEN RAY PACKER, OF NEW ROCHELLE, NEW YORK.

PROTECTIVE HEATING SYSTEM FOR RAILWAY SWITCHES AND THE LIKE.

Application filed December 28, 1920. Serial No. 433,591.

To all whom it may concern:

Be it known that I, EBEN RAY PACKER, a citizen of the United States, residing at New Rochelle, in the county of Westchester and State of New York, have invented new and useful Improvements in Protective Heating Systems for Railway Switches and the like, of which the following is a specification.

10 This invention relates to the art of protecting railway switches, movable point frogs and similar railway devices from interruption to their proper operation by the accumulation of snow and ice under severe 15 weather conditions, and consists of an improved construction and arrangement of electrical heating devices particularly adapted for obtaining a high degree of efficiency in installations of this character, and which 20 moreover are capable of being readily and inexpensively installed. My improved arrangement is further particularly designed for the concentration of the heat where most desired, between the main rail and the switch 25 point and so as to provide for drainage and the heating elements are further particularly adapted for installation in varied spaced relation to accommodate them to variations 30 in the different switch and other structures, and are further adapted to be rigidly secured in position without danger of displacement and possible obstruction to the 35 movable parts.

As is well known the interruption to railroad traffic caused by severe winter storms, is a considerable and costly factor in railroad operation at which time to maintain the proper operation of the switches and other devices not only is difficult and costly, but is 40 accompanied by considerable danger to life where men are required to sweep out the switches which has been the common practice at important switch points. While many 45 forms of heating devices have been proposed and tried out for the melting of snow adjacent to switch points, no substantial degree of success has been attained particularly by reason of the difficulties and excessive cost of installation, incident to the varied spacing of the ties and mechanical parts of the structures until the development, of recent date, of portable electrical heating

units, adapted to be readily positioned beneath the rails and distributed as the spacing of the ties and other parts permit. While these separable sealed heating units have to a large degree solved the problem, there are still objections present in the conditions of their use, for the reason that the position of the heaters embedded in the ballast, subjects them to the most severe condition resulting from the collection of water from the melted snow and ice. As a result thereof, these devices are adapted for temporary installation only requiring a duplication of installation cost from year to year in their practical use.

The improved device and arrangement of the present invention has for its purpose to provide a heating installation which will possess the proven advantages of the separable heating units or elements with respect to adaptability to the varied conditions of spacing, and which will moreover overcome the objections aforesaid in a manner allowing for permanent installation of the heating elements in an arrangement whereby they are not subjected to excessive depreciation and whereby they will possess other important advantages not heretofore obtained. For the latter purpose I employ heating elements or units of improved design and of size adapted to permit of their being secured to the rail and desirably interposed between the rail and the movable switch point, and thereby positioned within the space that it is most important to protect from the accumulation of snow. In my improved arrangement the heating elements are suitably elevated to be protected from drainage water, and accordingly may be permanently installed, and by their location within or immediately below the area to be protected the maximum heating efficiency is derived therefrom. A particular feature of my improved installation consists in the arrangement of the heating elements, so that they will be in sufficiently close proximity to the ballast so that the latter will be heated sufficiently to provide for drainage but with the heaters sufficiently elevated to be protected from the drainage water.

Other important features and advantages of my present invention will be understood

by reference to the accompanying drawings wherein like reference numerals are applied to the corresponding parts in the several views.

5 In the drawings:

Fig. 1 is a view in side elevation illustrating the improved type of heating element employed.

10 Fig. 2 is a view in cross section through the two rails and coating switch points of a railway switch, with the heaters installed in accordance with my invention.

15 Fig. 3 is a plan view of a switch layout having the improved heating elements incorporated therein in the arrangement of my invention.

20 Fig. 4 is a sectional view corresponding to a portion of Fig. 2 and illustrating a suitable modification in the arrangement of the heating elements.

Fig. 5 is a view similar to Fig. 1 illustrating the heating element in the modified form of Fig. 4.

25 Fig. 6 is a plan view of a switch layout having the features of my invention incorporated therewith in a modified arrangement.

30 Figs. 7 and 8 are detailed views thereof taken at right angles and illustrating the suspension of the heating elements from the base flange of the rail.

Fig. 9 is a side elevational view thereof.

35 Figs. 10 and 11 illustrate a suitable modification in vertical cross section, and plan wherein one of the heating elements is supported upon a special switch plate.

40 In accordance with my present invention I employ portable electrical heating units of standardized length and capacity, which are complete and tightly sealed at the point of manufacture, and adapted to be variously spaced in their distribution and connected in multiple or series as required to proportion the resistance with relation to the voltage 45 of the service available at the locality of their use. A desirable heating unit of this type is indicated in Fig. 1, wherein *a* indicates the completed unit composed of a

50 length of copper tubing 1, enclosing a coil 50 of resistance wire 2 extending lengthwise therethrough and insulated from the tube by means of a powdered silica packing 3 and at its extremities connected to terminal extensions or binding posts 4 having threaded 55 thereon the usual terminal securing nuts 5.

The heating units are further provided with radiating washers 6 as indicated, which are in the form of perforated discs fitted externally onto the tubing to increase the radiating surface. The heating elements so formed are preferably proportioned in length with respect to the normal spacing between the tie rod brackets of the switch point connections so as to permit of their being positioned intermediate of the brackets as best

illustrated in Fig. 3, and the heating units further are provided with securing clamps 7 adapted to be welded to the rail or supporting member, whereby they are rigidly supported in position without danger of 70 displacement and possible obstruction to the movement of the switch point.

The arrangement of my improved heating system wherein, as best shown in Fig. 2, the separable and standardized heating units are 75 secured directly to the rail web within the space enclosed by the rail and switch point, as will be appreciated concentrates the heating effect where most desired, and in addition permits of the units being assembled in 80 varied spacing relation to suit the specific conditions encountered in a switch structure. Installation of the heaters is therefore particularly simplified in that the heaters are installed as completed units, which when secured in position as the spacing permits, may be readily connected in the plural series arrangement by means of connecting wires 8 to suit the requirements of the particular energizing circuit available. 90

In accordance with a further feature of my invention as best understood by reference to Fig. 2, the securing clamps are formed suitably to support the heating units away from the rail whereby the radiating washers thereof are out of contact with the rail from which it results that a negligible amount of the heat is transmitted by conduction to the rail. The arrangement of 95 the heaters as described is further advantageous, in that being positioned beneath the rail head they are to a substantial degree protected from being displaced by workmen in the cleaning out of the switches, and the permanent installation of the heating units 100 by spot welding as contemplated reduces danger of displacement to the minimum. The heating units thus installed as will be understood, may without objection be left 105 permanently in position with substantial economy.

The heating units shown, and which I 110 preferably employ are commercially known as a Nacrome heating coil and are particularly well adapted for the purpose in that they are to a large degree flexible permitting deformation where required for purposes of clearance and moreover may be galvanized or otherwise protected against corrosion. 115

120 As will be understood the heating elements and arrangement thereof in my improved protective system may be variously modified without departing from the scope 125 of my invention. For instance as illustrated in Figs. 4 and 5, I have shown a suitable form of double heating element secured in position by a suitably modified clamp adapted to give increased heating effect where desired. 130

In Figs. 6 to 9 there is illustrated an approved modified installation in accordance with my invention. As here shown the heating elements *a* are secured to a base flange 5 of the rail so as to be suspended below the rail in slightly spaced relation thereto, and in close proximity to the ballast whereby the latter is heated to a substantial degree to promote proper drainage. In this arrangement as indicated, the heating elements may desirably be interposed between the ties and the elements may be provided with suitable wire clips or clamps 7', adapted to clamp over the upper surface of the rail flange, 15 and in this position are desirably secured by spot welding to provide a rigid installation. In this type of installation the heating elements may desirably be of the form illustrated in Figs. 7 and 8 with the looped ends 20 extending inwardly to underlie the space between the switch point and rail, whereby the heaters occupy the area within the vertical plane of the rail end switch point so that a substantial amount of heat will rise up 25 through the space between the rail and point as is desired. By so arranging the heating elements, they are suitably elevated to be protected from the drainage water and, moreover are protectively supported beneath 30 the rail flange so that danger of displacement in track work is minimized.

In Figs. 10 and 11 I have illustrated a special form and arrangement of the heating elements as applied to the switch plate. 35 As here shown the switch plate 14 providing a sliding bearing for the switch point is specially formed with a suitable recess 15 to receive therein the heating element which as here shown corresponds to the 40 heating element of Figs. 5 and 8, but wherein the radiating washers are omitted and the outer extremities are upturned as shown. In this arrangement of the heating element it is in direct contact with the switch bearing plate, whereby the latter will be heated to a considerable degree by conduction, and the heating element is slightly spaced from the rail whereby there will be no substantial heat loss thereto.

45 The heating devices as described are particularly advantageous in that they may be coupled up in situ without interfering with the moisture proof closure of the individual units and the latter are particularly well adapted to permit of transportation without damage thereto. The improved manner of installation offers no interference to ordinary track work, such as surfacing, lining, renewal of ties, etc., which may all 50 be accomplished without affecting the heater installation. My improved system may be readily varied to suit any particular form of electric current, and adjusted to any changes in the current available, and in addition the heated area may be made larger

or smaller as may be desired. The heating current may be controlled by a switch at any desired location so that the heating means so formed may be attended to by an employee having other duties such as signal 70 man or other operator.

Having described my invention, I claim:

1. A protective heating system for railway switch points and the like having in combination with the rails and movable switch points, a plurality of separable, sealed electrical resistance heating units rigidly secured to the rail and connected in series arrangement to provide the resistance value required for the circuit to which they are connected, and said heating elements being supported in spaced relation to the rail and in close proximity to, but above the ballast, substantially as described. 75

2. A protective heating system for railway switch points and the like having in combination with the rails and movable switch points, a plurality of separable, sealed electrical resistance heating units rigidly secured to the rail and connected in series arrangement to provide the resistance value required for the circuit to which they are connected, and said heating units being supported in spaced relation to the rail and in close proximity to, but above the ballast, and arranged to underlie a portion of the rail, substantially as described. 80

3. A protective heating system for railway switch points and the like having in combination with the rails and movable switch points, a plurality of separable, sealed electrical resistance heating units rigidly secured to the rail and connected in series arrangement to provide the resistance value required for the circuit to which they are connected, said heating units being suspended beneath the base flange of the rail and in spaced relation thereto, substantially as described. 100

4. A protective heating system for railway switch points and the like having in combination with the rails and movable switch points a plurality of similar, self-contained electrical resistance heating units rigidly secured to the rail and said heating units being supported in spaced relation to the rail and in close proximity to, but above the ballast and said units being of a size and positioned whereby they protectively underlie the rail. 110

5. A protective heating system for railway switch points and the like having in combination with the rails and movable switch points a plurality of sealed electrical resistance heating units rigidly secured to the rail and connected in series arrangement to provide the resistance value required for the circuit to which they are connected, such heating units being supported in spaced relation to the rail and in close proximity to, 125

but above the ballast, each of said units being arranged to underlie the base of the rail and formed of a tubular element having a reversed bend and parallel lengths arranged transversely of the rail and terminal extremities at one side thereof, substantially as described.

In testimony whereof I have signed my name to this specification in the presence of two subscribing witnesses.

EBEN RAY PACKER.
